METHOD OF SIFTING

Paul Naeher, Evanston, Ill., assignor to B. F. Gump Co., Chicago, Ill., a corporation of Illinois

Application August 2, 1940, Serial No. 349,918

2 Claims. (Cl. 209—322)

The present invention relates in general to a gyratory sifter and is more particularly concerned with the improvements therein for increasing the capacity and efficiency thereof.

Heretofore, in some types of rotary sifters it has been the practice to use cleaners on the bottom only of the sieve or bolting cloth, while in others it has been the general practice to utilize cleaners on the top only of the sieve or bolting cloth.

In the type using bottom cleaners, small cleaning devices were usually confined for movement within limited areas below the sieve or bolting cloth, these devices usually having tufts of bristles or were small pieces of cotton belt frayed on each end arranged to engage and sweep the under surface of the cloth during the sifting operation. Rubber balls have also been used for such purpose. On the other hand, in the type having top cleaners; locust seeds, coffee beans, wheat and the like were utilized as the cleaning instrumentalities, these being supplied with the material to be sifted to the upper surface of the sieve or bolting cloth to travel with the material over the upper surface of the sieve and be discharged with the tailings from which they were separated in some suitable manner and returned to the head end of the sifter where they were again mixed with the materials being bolted.

To my knowledge, the two arrangements described above have always been utilized separately and insofar as I am aware there has not until my present invention been any attempt to coordinate the two arrangements in a single sifting apparatus so as to secure the added benefits resulting from the simultaneous cleaning of both the upper and lower surfaces of the bolting cloth. It has been discovered that by utilizing a double cleaning arrangement with cleaning instrumentalities acting simultaneously upon both the upper and under surfaces of the sieve or bolting cloth, the sifting capacity per square foot of bolting surface is materially increased over its capacity when only one of its surfaces is being cleaned. From tests which have been conducted on sifters utilizing my improved double cleaning arrangement, this increase has been shown to be as much as approximately thirty-five per cent over the capacity obtained when utilizing cleaners only on the under side of the sieve or bolting cloth.

It is a primary object of the herein-described invention to provide improved sifter apparatus embodying a novel cleaning arrangement for the sieve or bolting cloth, wherein cleaning instru-

mentalities coact to increase the bolting capacity of the sieve or bolting cloth by simultaneously cleaning both its upper and under surfaces.

It is a further object of the present invention to provide an improved sifter apparatus construction to increase the capacity and efficiency of the sieve or bolting cloth utilized therein.

It is also an object of the invention to provide improved supporting means for the sieve housing.

Another object of the herein-described invention is to provide sifter apparatus embodying a novel driving arrangement.

Still another object is to provide a novel method for sifting material which may be practiced by the utilization of my improved apparatus.

Other objects and features of the invention will more fully appear from the following detailed description taken in connection with the accompanying drawings which illustrate a preferred embodiment thereof, and in which:

Figure 1 is a top plan view of a sifter constructed according to the present invention, a portion of the cover thereof being cut away to disclose the interior construction adjacent this end of the sifter;

Figure 2 is a longitudinal section through the same, taken substantially on line II—II of Figure 1;

Figure 3 is a transverse sectional view through the same adjacent the outlet end for the bolted material, taken substantially on line III—III of Figure 2;

Figure 4 is a plan view of the sifter with the cover removed as seen when looking from above the top bolting cloth or sieve, this view showing the disposition of the means for supplying the cleaning instrumentalities to the upper surface of the bolting cloth or sieve;

Figure 5 is a transverse sectional view showing the lower bolting cloth or sieve and the connection therefrom to elevating means for the cleaning instrumentalities for the upper surface of the bolting cloth or sieve;

Figure 6 is an enlarged fragmentary sectional view showing details of the elevating means for the objects utilized for cleaning the upper surface of the bolting cloth or sieve, taken substantially on line VI—VI of Figure 4;

Figure 7 is a fragmentary sectional view showing the arrangement of additional screens below the bolting cloth or sieve and the disposition of the cleaning devices for the under surface of the bolting cloth or sieve; and

Figure 8 is a fragmentary view looking down upon the sifting instrumentalities, the bolting

cloth or sieve, first screen and second screen therebelow being successively cut away and showing a cleaning device for the under surface of the bolting cloth or sieve as it appears in plan view.

As shown on the drawings:

For illustrating the present invention, I have shown in the drawings an apparatus for sifting, screening or bolting flour for separating the same according to its particle sizes. The particular construction shown in the drawings is by way of example of one construction embodying the invention, and it is not intended to limit this invention to the particular construction or form of sifter shown.

The present invention may be utilized with sifters employing sieves or screens of any suitable or desired construction and any desired number of such sieves may be employed and arranged to provide the desired number of separations and passes of the material to be sifted.

More specifically, the illustrated construction comprises a sieve or screen housing, as generally indicated at 19, of the usual rectangular construction. This housing is supported above a fixed base structure 11 by means of four wobble posts 12 which are arranged in quadrature.

Each wobble post is connected at its lowermost end through a universal joint 13 to the base structure and at its uppermost end through a universal joint 14 to the bottom of the housing.

As clearly shown in Figures 2 and 3, the base structure also has supported thereon the driving mechanism for the sifter. For this purpose there is provided substantially at the center of the base structure a bracket 15 for supporting a vertically disposed bearing 16 which has rotatably mounted therein a shaft 17. Fitted to the uppermost end of this shaft is a suitable flywheel 18 which carries an off-center bearing 19 that forms a journal box for a center pin 20 which is part of spider 21 fastened to the sifter housing. With such an arrangement, a circular or gyroscopic movement is imparted to the sifter housing during operation of the sifter.

At one side of the base structure there is provided a driving motor 22 which is supported upon a suitable angle bracket 23 with its driving shaft extending vertically and carrying at its uppermost end a suitable driving pulley 24, this pulley being connected through a suitable flexible connection such as a belt 25 with the flywheel 18. It will be noted that this arrangement provides a direct connection between the motor and flywheel and dispenses with the use of speed changing gears and other complicated driving mechanism. In operation, driving of the flywheel imparts a gyroscopic movement to the housing, this movement being permitted by the off-center bearing and center pin and through the use of the previously described universal joints in the wobble post construction.

The top of the sifter housing is provided with a suitable cover 26 which is provided centrally at one end with an opening 27 for the admission of material to be sifted therein. As shown in Figures 1 and 3, the interior of the housing is separated transversely into separate compartments by means of a longitudinally extending partition 28, each of these compartments being equipped with one or more bolting cloths or sieves for sifting the material supplied thereto. The material entering the inlet 27 is divided into two portions by the uppermost edge of the partition 28 which extends diametrically across the opening 27. The partition 28 cooperates with

inwardly spaced side walls 29-29 to form the sifting compartments within which the sieves are disposed. The side walls 29-29 being inwardly spaced from the adjacent side walls of the housing 5 providing lateral passages 30-30 which extend along the sides of the housing and communicate with a collecting compartment 31 extending the entire width of the housing and terminating in a vertically extending compartment 10 32 at the discharge end of the housing. The lowermost end of the compartment 32 is provided with an outlet opening 33 by means of which the sifted or bolted material may be conducted from the outlet compartment 32.

Referring to Figures 2 and 3, each sifting compartment has disposed therein a bolting cloth or sieve 34 which is supported on a suitable frame construction and which is downwardly inclined from the inlet end of the housing toward the 20 outlet end, the sieve 34 being terminated inwardly of the end wall of the housing at the outlet end thereof so that the tailings from the sieve 34 may be discharged into the upper end of compartment 32. The sieve 34 may be of any suitable material such, for example, as a silk cloth, such a cloth of suitable fineness being satisfactory when bolting flour. Spaced below the bolting cloth 34, there is provided a double screen which is preferably composed of an upper coarse screen 35 and a lower finer screen 36. For such purpose, an upper screen of No. 3 mesh and a lower screen of No. 8 or 10 mesh have been found satisfactory.

Below the sifting unit just described, there are 35 provided suitable drift boards 37-37 which are laterally downwardly inclined from the partition 28 to the side walls 29 where material falling upon the drift boards may be conducted through suitable openings 38 into the passageways 36. Thus the material which is bolted or sifted by the upper sifting unit will pass into the collecting compartment 31, while tailings from the sieve 34 will pass into the compartment 32 and drop onto a second or lower sifting unit which is inclined in the opposite direction from the first unit and composed of the bolting cloth or sieve 34', the coarse screen 35' and the fine screen 36'.

At the right end of the sifter as viewed in Figure 2, it will be noted that the second sifting unit extends across the compartment 32 so that tailings from the upper sieve unit will not be conducted into the outlet from the bolted or sifted material. At the opposite end of the lower sifting unit, there is provided a compartment 38 which is defined by one end of the housing and an inwardly spaced partition member 39. The compartment 38 communicates at its bottom with an outlet 40 through which the tailings may pass and be collected in any desired manner. At its uppermost end, the compartment 38 is closed by a screen 39', preferably of approximately No. 8 or 10 mesh, this screen being so chosen as to permit the passage of the tailings therethrough but oppose passage of locust seeds, coffee beans, wheat and the like, as shown at 40', which may be utilized as a cleaning instrumentality for the sieve as will hereafter be explained.

Below the lowermost sieve unit in the collecting compartment there is provided a drift board 41 which extends across the housing below the laterally disposed passages 30-30 and also the sifting compartments so as to receive the sifted material from the drift boards 37-37 under the upper sieve and also the sifted material from the lowermost sieve. The drift board 41 is in-

clined downwardly towards the outlet end of the sifter housing and is arranged to discharge sifted material into the lowermost end of compartment 32 below the portion of the lower sifting unit extending thereinto.

While I have shown an arrangement with two sieves, in this instance two passes, it will be appreciated that more sieves may be provided where desired to increase the capacity. Also, as many separations as desired may be provided for by using sieves with different meshes of silk or wire bolting cloth, and arranging the flow and outlet channels accordingly.

For assisting the material in its movement over the sieves or bolting cloths, suitable flights 42 have been shown along one of the walls 29 and the partition 28 above the upper sieves. Similar flights may in a like manner be associated with the lower sieves, if found necessary.

It has been found in operating sifters, that flour and soft materials have a tendency to paste or clog the meshes of the bolting cloth, and that the cleaner or more open the meshes are kept, the more efficient the bolting or sifting will be.

In my improved apparatus, provision has been made for cleaning the bolting cloth or sieve on both its upper and lower surfaces during the operation of the sifter.

For cleaning the upper surface, locust seeds, coffee beans, wheat or similar objects are introduced into the material being supplied to the sifter onto the upper surface of the sieves. These objects moving along with the material to be sifted in an even and regulated amount over the upper surface of the sieve provide a rubbing action which greatly facilitates the passage of the material through the bolting cloth or sieve and prevents to a large extent its becoming occluded. These objects pass onto the lower sifting unit with the tailings from the upper sifting unit, and since these objects are of such size that they will not pass through the screen at the upper end of the compartment 38, the objects will tend to accumulate at the bottom of a tubular passage 43 at the outermost corners of the sifting compartments at the head end of the sifter. Openings 43' as shown in Figures 5 and 6 are provided in the walls 29 at the bottoms of the tubular passages 43 to admit the objects thereinto. Disposed within each of the passages 43, there is provided a spiral screw or ramp 44 which leads to a collecting container 45 at the top of each sifting compartment of the apparatus above the first sifting unit. The objects may pass from the container 45 automatically through a hinged door 46 so as to again enter and come into with the material being supplied to the sifter. Due to the gyroscopic movements of the sifter housing, the objects will be caused to be automatically moved up the spiral ramp and elevated from the bottom portion to the top portion of the sifter and thus continuously circulated over the upper surfaces of the bolting cloths or sieves with the material being sifted.

In apparatus of this type as previously constructed, it has been the custom to provide a single screen below the bolting cloth or sieve. This screen was usually of coarse construction and in the event that any particles should break off from the locust seeds, coffee beans, wheat or other objects being utilized to clean the upper surface of the bolting cloth or sieve, or if the bolting cloth or sieve should become torn or a

hole become worn in it, these particles and objects could pass through the coarse screen and be discharged with the bolted material. While these objects and particles thereof were not of such a nature as to endanger the health of those utilizing the bolted product, nevertheless their presence in the bolted material tended to produce a lower quality product. In order to prevent the passage of either the objects or particles thereof into the finished product, I have provided a finer screen, in this instance the screens 36 and 36' which will effectively prevent the passage of the objects or particles into the finished product and consequently enhance the quality of the same.

In order to clean the under surface of the bolting cloth or sieve, I have provided cleaning devices as shown in Figures 7 and 8 in detail. In general, these devices comprise members 47 which may be molded or otherwise formed from any suitable material in the shape of a figure 8. One of the loops as shown at 48 is larger than the other as shown at 49. These two loops are connected by a bridging portion 50, and the loop 48 is preferably of flat or plain construction while the smaller loop 49 is offset as shown in Figure 7. At the bridging portion of the member, there is provided a rounded protuberance 51 which may be the head of a rivet having a bifurcated shank portion which extends through a suitable opening in the bridging portion 50. The ends of the shank of the rivet may be spread apart to securely hold the rivet in position. The head of this rivet forms a fulcrum upon which the member 47 may turn, slide and be rocked to cause the loop 48 and 49 to rub and tap against the under surface of the bolting cloth or sieve during the gyroscopic movement of the sifter housing. Moreover, these cleaning devices will move at random and continuously strike the under surface of the bolting cloth at different points during the operation of the apparatus.

It will be noted that this tapping action tends to vibrate the bolting cloth transversely and move it in a direction against the direction of movement of the particles of material passing therethrough.

It has been found that by combining the rubbing and tapping action of the cleaning devices 47 with the cleaning action of the objects such as locust seeds, coffee beans, wheat or the like, which may be supplied to the top surface of the bolting cloth, the sifting capacity of the bolting cloth or sieve is materially increased over that which would be obtained when the bolting cloth is cleaned only on one side.

As shown in Figure 7, the cleaning devices 47 are positioned between the bolting cloth and the screens disposed therebelow and the devices are supported on the uppermost of the screens over which the devices will be automatically moved during the operation of the apparatus.

It is thought that my improved sifting method will be readily apparent from the foregoing description of the apparatus by means of which the method may be practiced.

From the foregoing description, it will be apparent that the present invention provides an improved sifter apparatus and novel method of sifting, the apparatus embodying a novel cleaning arrangement for the sieve or bolting cloth, wherein cleaning instrumentalities coact to increase the bolting capacity of the sieve or bolting cloth by simultaneously cleaning both its upper and under surfaces; apparatus of the here-

indescribed type having increased capacity and efficiency; which incorporates improved supporting means for the sieve housing; which is provided with a novel driving arrangement; and which utilizes a simple and effective construction in which increased sifting capacity may be obtained and a high quality product produced.

It is, of course, to be understood that although I have described in detail a preferred embodiment of my invention, the invention is not to be thus limited, but only insofar as defined by the scope and spirit of the appended claims.

I claim as my invention:

1. The method of sifting flour in a shaking type of sieve which comprises placing upon the upper surface of a sieve the flour to be sifted, introducing a plurality of freely movable small objects of a size considerably larger than the flour particles and having a density equal to or greater than that of the flour particles into the flour for cooperating with the upper surface of the sieve to subject particles of the flour and the sieve to a rubbing action to force particles of flour through the sieve, removing tailings and objects from the top of the sieve, separating said objects from any tailings and continuously returning said objects to the top of said sieve, and simultaneously therewith transversely tapping the under surface of the sieve at a plurality of points to jar the sieve and movable objects

15
20
25
30

thereon thus aiding in freeing particles clogging the interstices of the sieve and to enhance the action of the freely movable objects in rubbing particles through the sieve whereby the aggregate of flour passing through the sieve is substantially greater than that attained by the use separately of said rubbing and tapping actions.

2. The method of sifting flour in a vibratory type of sifter, which method comprises placing upon the upper surface of a bolting sieve the flour to be sifted, introducing into the flour a plurality of freely movable small objects of a size considerably larger than the flour particles and having a density equal to or greater than that of the flour particles for cooperating with the upper surface of the bolting sieve to create rubbing action upon the bolting sieve and thereby force particles of flour therethrough, removing tailings and objects from the bolting sieve, separating the objects from any tailings and continuously returning the objects to the top of the bolting sieve, and simultaneously therewith tapping the under surface of the bolting sieve with a plurality of other and larger objects freely movable upon a reticulated surface beneath the bolting sieve, thereby aiding in freeing the flour particles from the bolting sieve and enhancing the action of the rubbing objects.

PAUL NAEHER.
